UNITED STATES PATENT OFFICE.

WESLEY G. NICHOLS, OF CHICAGO HEIGHTS, ILLINOIS, ASSIGNOR TO AMERICAN MANGANESE STEEL COMPANY, OF CHICAGO, ILLINOIS, A CORPORATION OF MAINE.

DREDGE-BUCKET.

1,176,376.

Specification of Letters Patent Patented Mar. 28, 1916.

Application filed June 26, 1915 Serial No. 36,464.

To all whom it may concern:

Be it known that I, WESLEY G. Nichols, a citizen of the United States, residing at Chicago Heights, in the county of Cook and State of Illinois, have invented certain new and useful Improvements in Dredge-Buckets, of which the following is a specification.

My invention relates to dredge buckets and has particular reference to an improvement in the bucket at the point of connection to an adjacent bucket.

It will be understood that buckets such as contemplated by me are intended for use in an endless chain, a series of buckets being directly united through the agency of pivot lugs or indirectly united by means of connecting links. The buckets sought to be improved by me are each of relatively great size, one bucket often weighing as much as four thousand pounds. To withstand the shocks and wear, as well as the strains imposed in service due to their own weight and the loads carried thereby, it has been found necessary to form the buckets of massive proportions and to utilize special steel alloys, such as manganese steel. However, one of the inherent characteristics of manganese steel is its relatively great coefficient of expansion which presents foundry problems not present in the handling of ordinary cast steel. The difficulties experienced in casting ordinary steel where relatively thin and thick sections are joined are accentuated in the casting of manganese steel, and it is to alleviate one of these difficulties that I provide for the present improvement in the form of the bucket.

It will be understood also that the individual buckets are joined to adjacent buckets either directly or indirectly by means of lugs, the connection being in the form of apertured lugs cast on the bottom of the bucket. It is necessary to provide a bushing for the connecting pin and as the pulling and wearing strain occurs only at one side of the pin the bushing employed is usually in the form of a semi-circle in cross section, the edges of the bushing being fitted against shoulders formed integral with the eye of the bucket. Inasmuch as manganese steel is exceedingly hard and cannot be worked with ordinary tools, it is necessary to grind any portions which require finishing and the space within the eye being closed to any common form of grinding tool the integral

shoulders against which the edges of the bushing are intended to abut are commonly left undressed or unfinished, that is, having a relatively large fillet, making the fitting of the bushing thereto a matter of difficulty. Not only is the fitting of the bushing made difficult, but the fit at best is secured by rounding the corners of the bushing, and the tendency of the bushing is to rotate, the wear and distortion of the bushing begins at an early stage, thus requiring frequent renewal.

An object in the present construction is to solve the foundry problem as to the joining of thin and thick sections and to obviate the difficulties as to the fitting of the bushing, the result being secured by inserting a filler in the place of the portion which has heretofore been integrally formed in the eye of the bucket. In one of the forms of construction shown a still further advantage is secured in that the space within the eye is more open and accessible to the action of water in the heat treatment which follows the formation of manganese steel castings.

In order to enable those skilled in the art to fully understand my invention attention is directed to the drawings which form a part of this specification and where like numbers represent like parts.

Figure 1 is a side elevation of my improved bucket. Fig. 2 is a vertical sectional view through the rear eye showing a modified form; and Fig. 3 is a plan view of a bucket constructed in accordance with my invention.

In an improved form the bucket may consist of side walls 10, a cutting lip 11 secured to the bucket by means of rivets 12 and provided with a lower wall or floor 13. On this lower wall are carried a pair of eyes 14 and a single eye 15, the space between the eyes 14 being substantially equal to the width of the central eye 15.

The buckets are cast in a position 90 degrees removed from that indicated in Fig. 1, that is, with the eye 15 at the top, at which point a riser is located, the pouring gate being at one side and the metal being supplied near the lower portion of the casting when in the position indicated. The interior of the eye 15 is usually chilled which results in the freezing of the metal between the riser and the lower portion of the bucket before the metal therebelow has had opportunity to

- sec. Therefore, as the casting of the lower portion continues the continuation thereof pulls hot metal from the unsolidified portion adjacent to the eye 16, this resulting in the formation of weaknesses at that point. I propose to alleviate this difficulty by reducing the section of metal at a point beneath the eye 16 and to thereby eliminate some of the existing problems and provide for a better combination of the pin and bushing. To this end I entirely eliminate the metal on the inside of the eye, as shown in Fig. 1, and substitute therefor a filler 17 of hard metal, the inner surface of which is curved to the radius of the pin 22 which is to occupy the eye, and which is provided with shoulders 23 which may be made square, the finishing or grinding being done prior to the installation of the filler in the eye. After the filler 20 is inserted a portion 23 of the metal of the bucket is peened or hammered over the same. The filler is then substantially an integral part of the bucket. The bushing 19 of bearing metal as shown is semi-circular in cross section and its square edges fit nicely and abut the ground edges of the filler. Relative movement of the bushing and filler is prevented and such wear is therefore avoided. It will be seen that by eliminating the metal formerly located at the periphery of the filler 17 I am able to maintain the section practically uniform around the eye and contiguous thereto, a section of 21 being substantially equal to that of metal surrounding the eye. Consequently as the heat treatment and cleaning operations are carried out prior to the installation of the filler, the interior of the eye is much more reversible and many advantages accrue as a result thereof.
- 60 In the construction shown in Fig. 2 I have eliminated a quantity of metal which would ordinarily present several difficulties having turned the section at the objectionable point, and I insert in place of the metal eliminated 45 a filler 24 which likewise has square shoulders 25 against which the edges of the bushing 26 may abut. This construction may be found to be of advantage in some instances. It will be noted in the construction shown 65 in both Figs. 1 and 2 that the hard metal fillers 17, 24, are generally wedge-shaped in cross section and occupy similarly shaped recesses in the eye. This provides for an accurate fit and the fillers are more easily 55 located in position.
- Obviously other modifications than those suggested may be made and such modifications as are within the scope of my claims I consider within the spirit of my invention.
- 70 I claim:
1. A dredge bucket composed of a bushing of alloy steel and provided with apertured bungs, the combination of a pin, the diameter of the aperture in one of said bungs being substantially greater than the diameter of said
- pin, a filler of hard metal permanently fixed in said last-mentioned aperture, and a bushing of bearing metal also seated in said aperture, said filler and bushing when positioned providing a bearing for said pin, substantially as described.
2. In a dredge bucket composed of a casting of alloy steel and provided with apertured ears adapted to accommodate pivot pins, the aperture in one of said ears being of a cross sectional area materially greater than the corresponding area of said pin, the combination of a filler of hard metal fixed in said opening and occupying a substantial portion of the area not required by the pin, and a bushing of bearing metal occupying the remainder of the space not required by the pin, substantially as described.
3. In devices of the class described, the combination with buckets of alloy steel having pivotal members, of pins, said pins acting to unite a plurality of buckets through their pivotal members, at least one pivotal member of each bucket comprising a recessed solid part, the recess being of a diameter greater than the diameter of the pin which cooperates therewith, a hard steel part cooperating with said solid part, the inner surface of said hard steel part bearing against said pin, and a bushing of soft metal fitted between said solid part and said pin and abutting against said part of hard steel, substantially as described.
4. In buckets of alloy steel adapted to be fastened together to form a chain, the combination with the buckets, of pins, said buckets having forward and rearward pivotal members providing eyes or apertures therein, the rearward member of each bucket being adapted to engage a forward member of an adjacent bucket, said pins being adapted to be inserted in said pivotal members so positioned, the eyes or apertures in said rearward members being of larger diameter than said pins, a pair of bushings inserted in each of said eyes, one bushing of soft metal, another of hard metal, said bushing of hard metal providing shoulders and being located in the forward portion of said eye, said bushing of soft metal being located in the rearward portion of said eye with its edges abutted against said shoulders of said hard bushing, substantially as described.
5. In combination, buckets of alloy steel having forward and rearward pivotal members integral therewith, pins, each of said rearward members comprising a solid portion having a semi-circular recess of greater diameter than said pin, a non-circular recess opposite to and of greater size than said semi-circular recess, a filler of hard steel of irregular cross section fitted into said non-circular recess, the said filler having a recess which is truly semi-circular and of a diam-

- eter substantially equal to that of said pin, the edges of said filler providing square shoulders, and a bushing of soft metal semi-circular in section fitted into the semi-circular recess in said solid portion with its edges abutting against the square shoulders provided by said filler of hard metal, substantially as described.
6. In a device of the class described, 10 buckets of alloy steel having two front eyes and one rear eye, the rear eye of one bucket being adapted to be inserted between the front eyes of the succeeding bucket, said rear eye being provided with a length-wise semi-cylindrical cavity and a lengthwise substantially wedge-shaped cavity opposite thereto, a separate bushing fitted to said wedge-shaped cavity with the longitudinal edges thereof extending into said semi-cylindrical cavity, the face of each lying in a
- plane with the axial center of the eye, and means for holding said separate wedge-shaped bushing in said cavity, substantially as described.
7. A dredge bucket composed of alloy steel 25 and provided with forward and rearward apertured lugs, the outline of the aperture in said rearward lug being substantially one-half semi-cylindrical and one-half of angular outline, a hard metal filler fitted into the angular portion of the aperture, and a soft metal bushing fitted into said semi-cylindrical portion, substantially as described.
- Signed at Chicago Heights, Illinois this 21st day of June, A. D. 1915.
- WESLEY G. NICHOLS.
